DESIGN FOR A MUSICAL INSTRUMENT CASE

Max Frost, Brooklyn, N. Y.

Application November 6, 1936, Serial No. 65,744

Term of patent 14 years

To all whom it may concern:

Be it known that I, Max Frost, a citizen of the United States and resident of Brooklyn, in the county of Kings and State of New York, have invented a new, original, and ornamental Design for a Musical Instrument Case, of which the following is a specification, reference being had to the accompanying drawing, forming part thereof.

In the drawing:

Fig. 1 is a front elevation of a musical instrument case showing my new design.

Fig. 2 is an end view thereof.

Fig. 3 is a top plan view of the same.

I claim:

The ornamental design for a musical instrument case substantially as shown.

MAX FROST.
